MACHINE TOOL

Fred A. Parsons, Milwaukee, Wis., assignor to
Kearney & Trecker Corporation, West Allis,
Wis.

Application November 30, 1928, Serial No. 322,798

52 Claims. (Cl. 90—21.5)

This invention relates to machine tools and more particularly to transmission and control mechanism therefor.

It is a purpose of the invention to provide an improved transmission which is in part hydraulic and in part mechanical.

A further purpose relates to improved control mechanism which is in part hydraulic and in part mechanical.

10 Another purpose relates to an improved relationship between spindle and table transmissions and improved control mechanism for the combination.

Another purpose relates to improved control mechanism incorporating a power shift controlled either manually or from the power movements of the machine.

Another purpose relates to a power shifter capable of a variety of shifting movements such 20 for instance as to move a reverser to forward, reverse and neutral positions and to the selective control of such a shifter either manually or from power movements of the machine.

Another purpose relates to a transmission arrangement and control to prevent operation of a spindle train when a table transmission is inoperative, or when the table transmission is operative at a rate other than a cutting rate, such as a quick traverse rate.

30 Another purpose relates to transmission and control mechanism productive of cycles of machine operation, controlled from the movements of the machine, and with various work and tool movements synchronized.

35 Another purpose is generally to simplify and improve the construction and operation of machine tools, and of transmission and control mechanism therefor; and still other purposes will be apparent from this specification.

40 The invention consists in the arrangement and combination of parts herein illustrated, described and claimed and in such modifications of the structure illustrated as may be equivalent to the claims.

45 In the drawings, the same reference characters have been applied to the same parts in each of the several views, of which:

Fig. 1 is a right side elevation of a milling machine incorporating the invention.

50 Fig. 2 is a front elevation of the same machine.

Fig. 3 shows a front elevation of certain units of the milling machine enlarged.

Fig. 4 is a plan view of the unit shown in Fig. 3, partly in section along line 4—4 of Fig. 3.

55 Fig. 5 is a plan view of part of the unit shown

in Figs. 3-4 partly in section along line 5—5 of Fig. 3.

Fig. 6 is a partial transverse section along line 6—6 of Fig. 4.

Fig. 7 is a partial transverse section along line 5—7 of Fig. 4.

Fig. 8 is a diagrammatic view showing the relationship and construction of certain table transmission and control mechanism.

Fig. 9 shows a vertical section taken along line 10 9—9 of Fig. 2.

Figs. 10 and 11 show different table control dogs.

Fig. 12 is a diagrammatic view showing the relationship and construction of certain table 15 transmission and control mechanism.

Fig. 13 is a diagrammatic view showing fast and slow transmission drives.

Fig. 14 shows a partial transverse section along line 14—14 of Fig. 13.

Fig. 15 shows driving means for an auxiliary pump.

Figs. 16 and 16a show details of a lost motion control device.

The milling machine includes a base or support 1, a table or support 2, reciprocably supported therefrom, a head or support 3 adjustably fixed on the base adjacent the table, and a spindle carrier or support 4 supported from head 3 for vertical movement. The spindle carrier 4 supports a rotatable tool spindle or tool support 5.

Transmission mechanism is provided for spindle 5 as follows:

A pulley 6, intended to be operated at constant speed, Figs. 1 and 13, is fixed on a sleeve 7 rotatably supported in a bracket 8 fixed on the bed 1. Fixed with sleeve 7 is a member 9 of a friction clutch generally denoted by numeral 10 and having a member 11 slidably keyed on a shaft 12 for movement to engage or disengage complementary friction surfaces on the members 9—11. Member 11 provides an extended hub or sleeve 13 upon which is fixed a friction member 14 adapted in the one direction of movement of the member 11 to engage a friction surface thereon with complementary friction surface 15 fixed with bed 1, forming a brake generally denoted by the numeral 15A. The arrangement provides a device operative in the one direction of movement of the hub 13 as a motion interrupting clutch to drive shaft 12 from pulley 6 and in the other direction of movement to form a brake for the shaft 12. Shaft 12 drives a shaft 16, Fig. 1, through bevel gears 17—18. Shaft 16 drives a shaft 19 through a rate changer generally de- 55

noted by the numeral 20 and consisting of different diametered gears 21—22 removable and interchangeable between ends of the shafts. Fixed on shaft 19 is a pinion 23 engaging gear 24 journaled in head 3 and prevented from axial movement, there being a shaft 25, Fig. 2, journaled for movement with carrier 4 and slidably splined in an axial bore of gear 24. Shaft 25 drives spindle 5 through bevel gear 26 fixed on shaft 25 and meshing with gear 27, fixed on the spindle.

The pulley 6 also drives a transmission for table 2 as follows: A fluid pump generally denoted by the numeral 28, Figs. 1—4—8—12, is driven from a shaft 29, which in turn is driven at either a fast or slow rate as will be described. Pump 28 actuates table 2 through a reversing valve generally denoted by the numeral 30, Figs. 4—8, and a hydraulic cylinder or motor 31 having a piston 32 fixed on a piston rod 33 with which table 2 is fixed for movement. Pump 28 may be of any suitable form but as here shown is of a construction similar to that fully shown and described in the United States Patent No. 1,678,050 issued July 24, 1928, and will therefore be only briefly described.

Housing portions 34—35 form a substantially closed casing 36, Figs. 1—4, fixed on a bracket or housing 37, which in turn is fixed with bed 1. A pump housing member 38, Fig. 4, fixed with member 34 extends within the casing 36 and removably fixed therewith is a pump housing member 39. Portions 40—41—42—43 of the housing members 38—39 form trunnions through which ports or passages 44—45 respectively open into opposite sides of a spherical chamber formed within the housing members 38—39 and having the sphere center coincident with the axis of shaft 29. The trunnions mentioned support ring members 46—47 fixed with a member 48 whereby rings 46—47 and member 48 form a unit supported and guided for movement about an axis passing through the center of the spherical chamber and at right angles with the axis of shaft 29. Journaled in member 48 is a shaft 49 having its axis at right angles to the trunnion axis about which member 48 moves and passing through the center of the spherical chamber in any position of member 48. Fixed on shafts 29 and 49 respectively are members 50—51. An intermediate member 52 is pivoted both with member 50 and member 51, the respective pivots being at right angles to one another and each passing through the center of the spherical chamber.

Member 50 driven from the shaft 29 drives intermediate member 52 which in turn drives member 51 and shaft 49 and the arrangement is such as to form four separate substantially closed chambers within the spherical chamber each of which is alternately expanded and contracted during each revolution of the parts if member 48 is positioned for the axis of shaft 49 to stand at an angle with the axis of shaft 29. The amount of volume change in each such chamber during revolution is proportional to the angle between the axes of shafts 29—49, being zero when the shafts are aligned. The position and form of ports 44—45 and of the various parts is such that the several chambers each rotate to maintain communication with the one port during expansion and with the other port during contraction whereby fluid supplied to the one port will be forcibly expelled from the other thus creating a positive flow of fluid through the pump. Although a

pump such as described will change its direction of flow as the position of shaft 49 is shifted to the one side or the other of the axis of shaft 29, in the present instance the pump is never reversed, other reversing means being provided as will be described. The shaft 49 and member 48 are, however, adjusted to regulate the volume of pump flow and for such purpose means will be later described.

Pump 28 may be driven either at a relatively fast rapid traverse rate or at a relatively slow feed rate as follows: Fixed with clutch member 9, Fig. 13, is a gear 53 meshed with pinion 54 fixed on a shaft 55 which may drive shaft 29 through a clutch generally denoted by the numeral 56a, and including a clutch member 56 fixed on shaft 55 and having a friction face complementary to a friction face 57 of a clutch member 58, the extened hub 59 of which is slidably keyed with the shaft 29, whereby the clutch members 56—58 may be engaged or disengaged according to the position of the member 58. Shaft 12 is extended forwardly and fixed thereon is a sleeve 60 having a portion 60a positioned within a bore 61 of a gear 62 rotatable on the shaft. The portion 60a of sleeve 60 is provided with a series of cam surfaces 63, Fig. 14, and positioned between such cam surfaces and the bore 61 are a series of rollers 64 spaced apart by portions 65 projecting from a member 66 rotatable on the sleeve 60. Member 66 together with rolls 64 is continuously urged in a direction to bind the rolls between the cam surfaces 63 and bore 61 by means of a spring 67 and when so positioned the rolls will drive the gear 62 from the shaft 12 but will not permit the shaft to be driven from the gear when the gear is driven at a higher rate than the shaft, the arrangement constituting an overrunning clutch device generally denoted by the numeral 62a. Gear 62 engages a gear 68 fixed on the clutch member 58 and the arrangement is such that when clutch 10 is engaged, pump shaft 29 will be driven from shaft 12 at a relatively low feed rate unless the clutch 56a is also engaged, in which case the shaft 29 is rotated in the same direction as before but at a faster or rapid traverse rate, the shaft 29 then being driven from the shaft 55. If the clutch 10 is not engaged, whereby spindle 5 is not rotated, then pump 28 cannot be actuated at a feed rate because shaft 12 is not actuated, but the pump may still be driven at a rapid traverse rate from shaft 55, according to the engagement of clutch 56a.

The channels leading from pump 28 to the cylinder 31 through reverser valve 30 are as follows: Referring to Figs. 3—4—8, the pump ports 44—45 respectively lead to the ends of closed channels 69—70 which terminate at the other end in ports 71—72, Figs. 6—7 respectively adjacent opposite ends of a movable valve stem or member 73 of valve 30. Adjacent port 72 are a plurality of ports 74—75, Fig. 7, and adjacent port 71 are a plurality of ports 76—77, Fig. 6. The ports 75—77 each communicate with a channel 78, Fig. 8, leading to the right hand end of the cylinder 31 and ports 74—76 each communicate with a channel 79 leading to the left end of the cylinder. The direction of rotation and all positions of adjustment of pump 28 are such that fluid enters the pump through valve port 72, channel 70 and pump port 44, and is expelled from the pump through pump port 44, channel 69 and valve port 71; and the valve stem 73 is cut away as shown in Figs. 6—7, to lead the fluid 75

from valve port 71 through the valve stem and valve port 76 into the channel 79 to the left end of the cylinder 31, when the valve stem is in the position there shown thus moving the piston 5 and table to the right. At the same time the cut away valve portions connect the channels for the fluid from the right hand end of cylinder 31 to be expelled through channel 78, valve ports 75-72 and channel 70 to pump port 45. If the 10 valve stem 73 is turned one quarter turn from the position shown in Figs. 6-7, the connection of the pump inlet and outlet ports with the cylinder will be reversed and the table will move in the other direction. The ports 71-72 are made 15 relatively large in order that an intermediate position of the valve stem will simultaneously open both the ports 71-72 to both of the channels 78-79 in which case the ports 71-72 will communicate with one another thus by-passing 20 the pump 28, whereupon the table will stop. In such case channels 78-79 are also freely connected thus by-passing the fluid from the one side of the piston to the other, whereupon the table may be moved by suitable manual means, 25 (not shown).

Shifting mechanism is provided for moving the various clutches and reversers by power and controlled either manually or in accordance with the movement of table 2.

Such shifting mechanism is hydraulically operated by the means of a pump generally denoted by the numeral 80, Figs. 1-2-8-9. Pump 80 may be of any suitable type but in this case includes a plunger 81, Figs. 4-9-15, which is moved in the one direction by the means of a cam 82, Figs. 9-15, fixed on shaft 55 and having a follower roll 83 pivoted on the one end of a pivoted lever 84, the other end of which actuates plunger 81 in the direction of movement thereof. In the other direction plunger 81 is actuated by a spring 85. The end of the plunger 81 operates in a chamber 86, Fig. 9, and in the one direction of plunger movement fluid will be drawn into the chamber from a reservoir 87 formed of the housing member 37 and the several housing members associated therewith, the fluid being drawn through an opening 88, a bore 89, a channel 90 communicating with an annular groove 91 in a closure member 92, a channel 93 from the annular groove 91 to a channel 94 in the closure member, and a valve consisting of a ball 95, yieldably seated by the means of a spring 96 in a manner to prevent fluid returning from chamber 86 to reservoir 87 through the valve.

In the other direction of movement of plunger 81 the fluid drawn into chamber 86 as described will be ejected through an opening 91, Fig. 9, and a valve consisting of a ball 98 pressed by a spring 99, and into a channel or chamber 100 communicating with a channel or pipe 101, Figs. 8-9-12, etc., the valve mentioned being operative to prevent a return of fluid from channel 100 to the chamber 86.

The chamber or channel 100 forms a fluid supply source for a variety of shifting mechanism later described, and associated therewith is an accumulator or reservoir of fluid continuously under pressure and generally denoted by the numeral 102A, Fig. 9. The accumulator includes 65 a substantially closed chamber 102 communicating with the channel 100 by the means of a channel 103 and capable of a variation of volume by the movement of a plunger or piston 104 slidably fitted in the bore 89. Piston 104 may move in 70 bore 89 against the resistance of a spring 105

and will do so whenever the volume delivered from pump 80 is greater than the fluid delivered through channel 101, thereby accumulating a volume of fluid in the chamber 102 and under pressure from spring 105. By virtue of accumulator 102A the volume delivered from pump 80 5 may be small relative to the instantaneous requirements of the shifters operated therefrom, the capacity of accumulator 102A being sufficient to provide for such instantaneous requirements. 10

The pump 80 operates continuously whenever the pulley 6 is operated since it is then always driven from shaft 55. This is to provide at all times for the operation of shifting mechanism 15 operable therefrom and in order that pump 80 shall provide for unusual as well as normal conditions of operation the volume of pump 80 is large relative to the total volume of fluid required for the normal operation of all the shifters over 20 a given period of time. Therefore in order to avoid power loss, mechanism is provided as follows:

The accumulator piston 104 moves in the bore 25 89 through which fluid is supplied to the inlet of the pump as described, and after piston 104 has moved sufficiently due to the accumulation of a desired volume of fluid in chamber 102, the end of the piston passes the intake opening 88 and closes the pump inlet. Thereafter the pump 30 consumes relatively very little power until such time as fluid is drawn from chamber 102, since the pressure of fluid from chamber 102 is prevented by ball 98 from acting against the plunger 81, until such time as fluid is drawn from the 35 chamber 102, thereby again opening the pump inlet. The operation is such that power is consumed substantially only in the amount actually required for the operation of the shifters actuated from the accumulator and pump. 40

The pump 28 as previously mentioned, is adjusted for various volumes to determine the rate of table feed when the pump is actuated at a feed rate. When operated at a quick traverse rate it is preferable that the pump should be adjusted to a position of predetermined volume, whereby the quick traverse rate will be constant and independent of the variation in feed rate. To accomplish the various adjustments mentioned the pump 28 is shifted to a predetermined 45 maximum volume whenever clutch 56a is engaged to engage the quick traverse drive and is again shifted to a feed position predetermined in accordance with the setting of a feed control device whenever the clutch 56a is disengaged to 50 drive the pump at a feed rate through the overrunning clutch device 62a. Mechanism for the above purposes is as follows:

A pump adjusting rod or plunger 106, Figs. 3-4-12, projects within casing 36 to engage suitable rack teeth 107, Fig. 9, thereon with complementary teeth 108 on the periphery of the ring member 46, the upper end of rod 106 being provided with a pivoted cam roll 109, Fig. 12, operating in a cam groove formed in a member 110, 60 Figs. 3-9-12, guided for movement to right or left in Fig. 3. Member 110 is connected for movement with a member 111, Figs. 3-5, by the means of abutments 112-113 Fig. 5 fixed with the respective members and a screw member 114 65 having a head portion 115 engaging abutment 112 to restrain the screw for axial movement with member 110, and having a portion 116 threadedly engaging the abutment 113. The screw 114 may be turned to increase or decrease the spacing of 70 75

the members 111—110 by the means of a hand lever 117, Figs. 1-2-3-5, fixed on a shaft 118, Fig. 5, upon which is also fixed a gear 119 engaging a gear 120 fixed on a shaft 121 having fixed thereon a bevel gear 122 engaging a gear 124 fixed on a shaft 125, the end 126 of which is slidably splined within an axial bore 127 of the screw 114.

The member 111 is movable by the means of power derived from pump 80 and controlled from 10 a lever 128, Figs. 1-2-3-4-5-12. Lever 128 is fixed on a shaft 129, Figs. 5-12, and moves a control plunger or valve member 130 of a feed and quick traverse control valve generally denoted by the numeral 131, Fig. 12, by the means of a 15 gear 132 fixed on shaft 129, an idler 133 and a gear 134 engaging both with idler 133 and with suitable rack teeth on the plunger 130. The plunger 130 at its lower end is provided with a recess 135 which in any position of the plunger 20 communicates with a channel 135a leading to the channel or pipe 101, whereby fluid from pump 80 and accumulator 102A is continuously available in the recess.

A port 136 communicates with recess 135 and 25 when the plunger 130 is moved upwardly in Fig. 12, registers with a port 137 communicating with a channel 138 leading to the end of a cylinder 139 having a piston 140. Piston 140 is extended for the opposite end 141 to work in an oppositely acting cylinder 142. When the plunger 130 is moved downward in Fig. 12, port 136 registers with a port 143 communicating through a channel 144 to the cylinder 142. The arrangement is such that piston 140 may be moved in the one 30 direction or the other by the means of fluid derived from pump 80 and accumulator 102A. When the plunger is in the position to supply fluid to the one of cylinders 139—142, the other is exhausted through channels provided by cutting away portions of plunger 130 at 146—147. The movement of the plunger brings such channels into communication with the one or the other of ports 137—143.

The piston 140 has fixed therewith a rack 148 40 engaging teeth 149 of a pivoted segment 150 which also has teeth 151 engaging suitable rack teeth 152 in an extension 153 of the member 111.

The member 111 when moved will move member 110 and the control rod 106 of pump 28 45 through mechanism previously described, and at the same time the quick traverse and feed control clutch 56A will be moved through mechanism as follows:

A piston 154, Fig. 9, operates in a cylinder 155 50 which communicates to receive fluid from the channel 138, Fig. 12, whenever the channel receives fluid, through a pipe or channel 156, Figs. 9-12, whereby piston 154 is forced to the left in Fig. 9 against the resistance of a spring 157. A lever 158 pivoted at 159 connects with piston 154 55 at the one end by the means of a fork portion 160 engaging a pin 161 fixed with the piston, and at the other end connects with clutch 56A by the means of a pivoted shoe 162 engaging an annular groove 163 in the extended hub 59 of clutch member 58.

When plunger 130, Fig. 12, is moved to admit fluid to channel 138, the clutch 56A, Fig. 13, will 60 by the mechanism described, be disengaged whereby to drive pump 28 at a feed rate through the over-running clutch 62a, Fig. 13, and at the same time the piston 140 will move to the right in Fig. 12, moving members 111—110 to the left. When the plunger 130 is moved to admit fluid to 65 channel 144 the pressure is released from piston

154, Fig. 9, and spring 157 will shift the lever 158 to engage clutch 56A whereby to drive pump 28 at a quick traverse rate and at the same time piston 140 will move to the left in Fig. 12, moving members 111—110 to the right. The member 110 has a total movement predetermined by the limited movement of piston 140 or by other suitable means, and the cam 110 is of relative form and position such that when member 110 is adjusted by screw 116 and lever 117, Fig. 5, relative to member 111, to the extreme of its adjustment to the right in Fig. 12, that is to say, to stand as far as possible from member 111, the roll 109 will move throughout the travel of member 110 in a lower portion of the cam groove and the pump 28 will be maintained in a position of maximum fluid delivery not only when clutch 56A is positioned for a quick traverse but also when the clutch is positioned for a feed. Under such conditions a shift of plunger 130, Fig. 12, to a feed position will result in a maximum feed. As the member 110 is adjusted by lever 117 to a position closer to the member 111, the roll 109 will at the end of the left hand or feed direction of movement of member 110 have moved progressively farther up the angular slot, the total upward movement at the end of the feed movement of member 110 determines the position of adjustment of pump 28 and the rate of feed. The lever 117 is movable with a pointer or index member 164, Figs. 2-3-5, movable against a chart or index scale 165 suitably graduated preferably in numerals, not shown, to indicate different rates of feed, and the connection of lever 117 for adjustment of member 110 is such that the indicator at all times remains positioned to indicate the feed which will result when a feed shift has been made.

The pump 28 may be considered as a rate changer of which portions are adjustable for 40 altering the rate of the table. The lever 117 and associated parts constitute a rate selector operable independently of the adjustment of the rate changer, that is to say, it can be set for a desired rate without adjusting the rate changer, which 45 may be later power adjusted by the operation of plunger 130.

The clutch 10 and brake 15A, Figs. 1-13, are 50 arranged to be shifted from pump 80 and accumulator 102A as follows:

A lever 166, Figs. 1-13, pivoted at 167 is connected at the one end with the clutch member 11 by the means of a pivoted segment 168 engaging an annular groove 169 in the hub of the clutch member. At the other end lever 166 has a portion 166a engaging a slot 170 in a piston 171, the opposite ends of which work in cylinders 172—173 respectively. The cylinder 172 is connected to be operated from fluid in the feed channel 138, Fig. 12, by the means of a pipe or channel 174, 60 Figs. 1-12-13, whereby the clutch 10 will be engaged by fluid from pump 80 whenever the plunger 130, Fig. 12, is shifted to a feed position. The cylinder 173 is similarly connected with the channel 144 by the means of a pipe or channel 175 65 whereby fluid from pump 80 will disengage clutch 10 and engage brake 15A whenever the plunger 130 is shifted to quick traverse position.

The reverser valve 30 is moved by the means of fluid derived from pump 80, as follows:

A hand lever 176, Figs. 1-2-3-16, is fixed on a sleeve 177 upon which is also fixed a gear 178 engaging suitable rack teeth in a valve plunger 179, Fig. 16. A channel 180 communicates with the channel 101 through a junction 181, Fig. 8, 75

with channel 136 whereby channel 180 is continuously supplied with fluid under pressure. A recess 182 in plunger 179 communicates with channel 180 in any position of plunger 179 and 5 supplies fluid to a passage or port 183 through the plunger. Ports 184—185—186 are positioned to receive fluid from port 183, one at a time, in different positions of plunger 179 respectively, and respectively communicate with different cylinders 10 187—188—189 through different channels 190—191—192. The cylinders 187—189 are arranged for opposite movement respectively of a piston 193 and will move the piston to the limit of its travel in either direction in accordance with the 15 position of plunger 179 to deliver fluid to the one or the other port 184—186.

Cylinder 188 actuates a piston 194, having a head portion 195 adapted to cooperate with a V notch or cam 196 associated with piston 193 in 20 a manner such that when piston 194 is actuated by positioning plunger 179 to deliver fluid to port 185 and cylinder 188, the piston 194 will move piston 193 to an intermediate or central position from either of the other positions to which it 25 may previously have been moved by cylinders 187—189. Fixed with piston 193 is a rack 197 engaging a segment 198 pivoted on stem 73 of valve 30, Figs. 4—8.

When plunger 179 is positioned for any cylinder 187—188—189 to receive fluid the other cylinders are opened for exhausting fluid contained therein, there being recesses or cut away portions 199a—199b, Fig. 8, provided for this purpose in the plunger 179 adapted to receive fluid from the 35 ports 184—185—186 and to by-pass such fluid along the plunger to return to the reservoir 87, Fig. 9.

By the construction described reverser 30 may be positioned by power derived from pump 80 40 and controlled from lever 176 in a manner to control the forward, reverse or stop of table 2.

The plunger 130, Fig. 12, may be shifted by power in accordance with movement of table 2 by the following mechanism.

45 A plunger 200, Figs. 4—5—10, adjacent plunger 130 is connected for movement therewith by the means of suitable rack teeth 201 on plunger 200 engaging a segment 202 fixed on shaft 129, and by the train previously described connecting shaft 50 129 with plunger 130. The connection is such that the one plunger is moved up when the other is moved down. Either upwardly positioned plunger may be shoved back down again by the means of dogs such as a dog 203, Figs. 8—10. 55 Since the dogs for either plunger and for either direction of table travel are similar in construction, only dog 203 will be described.

Referring to Figs. 8—10, the dog provides a body portion 204 adjustably fixed on table 2 by the 60 means of a T bolt 205 and T slot 206 and of a size suited to bring a latch 207 into a path of movement to contact the desired plunger 130 or 200, the latch being swiveled on a pivot pin 208, and limited for movement in one direction about 65 such pivot by contacting a portion 209 of the body, being normally pressed against such portion by a spring 210. Right and left hand dogs are used respectively pivoted for movement of the latch in different directions about the pivot 70 in accordance with the direction of table travel in which the dog is to be used, whereby the latch will operate the plunger in one direction of table travel but will swing about the pivot without operating the plunger in the other direction of table travel. There is provided a detent device 75

for plunger 130 generally denoted by the numeral 211, Fig. 12 and including cam portions or notches 212—213 fixed with plunger 130 to register with a suitably formed plunger 214 respectively when plunger 130 is in the different operative positions. Plunger 214 is strongly pressed by a spring 215 and the relationship is such that when the ports approach a position of registry the detent acts to quickly move the plunger 130 into a position of full registry independently of 10 the rate of dog and table movement, also to retain such position in spite of such force as may be exerted on the plunger by spring 210 during backward movement of the dog 203.

It is obvious that suitable dogs such as 203 may 15 be used to shift plunger 130 to either feed or quick traverse positions at any desired point or points in either direction of table travel.

The plunger 179, Fig. 8, may be shifted by power in accordance with the movement of table 20 2 by the following mechanism. A plurality of plungers 216—217, Figs. 4—5—11, are connected for opposite movement by the means of a pivoted segment 215 engaging suitable rack teeth in plunger 217 and also engaging a pivoted idler 25 gear or segment 218 which engages a pivoted segment 219 fixed with a segment 220 engaging suitable rack teeth in plunger 216. The plunger 216 is extended downwardly for suitable rack teeth thereon to engage a segment 221 fixed on 30 a shaft 222 journaled in an axial bore of the sleeve 177 and extending through the sleeve to be connected for movement therewith through a lost motion device generally denoted by the numeral 223. Lost motion device 223 includes an 35 abutment member 224 fixed on shaft 222 and positioned to be contacted in opposite directions by screws 225—226 respectively carried by ears or lugs 227—228 fixed on sleeve 177, whereby to move the plunger 179 from plungers 216 or 40 217. A movement of hand lever 176 to cause 45 a table movement through mechanism previously described will move the one or the other of plungers 216—217 upwardly. Either upwardly positioned plunger may be shoved back down again by the means of dogs such as dog 229, Figs. 8—11. Since the dogs for either plunger and for either direction of the table travel are similar only the dog 229 will be described. Referring to Figs. 8—11 the dog 229 includes a body portion 50 230 adjustably fixed on table 2 by the means of a T bolt 231 engaging the T slot 206 and having a downwardly projecting portion with angular faces 232—233 adapted to engage the ends of the one or the other of plungers 216—217 and move 55 the plungers downwardly during movement of the table; the body portion of different dogs being of a size sufficient to position the downwardly projecting portion in a path to contact the one or the other plunger which it is desired to move. 60

A detent device generally denoted by the numeral 234, Figs. 16—16a, includes a cam member 235 fixed with the shaft 222 and having a central notch 237 positioned between two cam surfaces and engageable by a plunger 238 pressed 65 by a spring 239 when the cam is in the central position of the movement with shaft 222. On either side of central notch 237 are cam surfaces 240—241 respectively adapted to urge shaft 222 in opposite directions. When screws 225—226 70 are each set up against abutment 224 whereby there is no lost motion in the parts connecting between cam 235 and plunger 179, a dog such as 229 acting on a plunger 216 or 217, will position the cam 235 for plunger 238 to enter the central 75

notch a little before the plunger 179 reaches a position to register port 183 with the port 185 of cylinder 188. In such case the plunger 238 acting against the angular sides of the central notch will quickly force the parts to a position of full registry of the ports 183-185, irrespective of the rate of table movement, and the reverser valve 30 will be immediately positioned to stop the table.

If, however, the one or the other of screws 225-226 is adjusted to provide sufficient lost motion between cam 235 and plunger 179, then in the corresponding direction of movement of cam 235 from a dog 229, the central notch 237 will completely pass the point of plunger 238 before the plunger has moved the ports 183-185 into registry sufficient to shift reverser valve 30 to stop the table, and immediately thereafter the cam 235 will shift the plunger 179 quickly past such registry of ports and into a position of port registry which will shift valve 30 to opposite position thereby reversing the movement of table 2. Such reversal of table movement may take place at either or both ends of the table movement accordingly as one or both of the screws 225-226 are adjusted for suitable lost motion between cam 235 and plunger 179.

What is claimed is:

1. In a machine tool the combination of a tool support and a work support, transmission mechanism for actuation of one of said supports including a reverser having forward, reverse and disengaged positions, three elements respectively operable to move said reverser to different of said positions from either other position, power means for movement of said reverser, and control means selectively operable to connect said power means to move said reverser through any of said elements one at a time.

2. In a machine tool the combination of a tool support and a work support, transmission mechanism for actuation of one of said supports including a reverser having forward, reverse and disengaged positions, a first element operable for shifting said reverser to said disengaged position from either other position, a second element operable for shifting said reverser to said forward position from said disengaged position, a third element operable for shifting said reverser from said disengaged position to said reverse position, each of said elements being operable to shift the reverser as described without passing through a third one of said positions, power means for movement of said reverser, and control means selectively operable to connect said power means to move said reverser through any of said elements one at a time.

3. In a machine tool the combination of a tool support and a work support, transmission mechanism for actuation of one of said supports including a reverser shiftable to forward, reverse and disengaged positions, three fluid operable elements respectively for movement of said reverser to different of said positions, a fluid source, and valve means receiving fluid from said source and shiftable to connect said source with any of said devices one at a time.

4. In a machine tool the combination of a tool support and a work support, a transmission for actuation of one of said supports including a reverser shiftable to forward, reverse and disengaged positions, three fluid operable elements respectively for movement of said reverser to different of said positions, a fluid source, valve means

receiving fluid from said source and adjustable to connect said source to different of said elements one at a time, and dog operated means for adjusting said valve means in accordance with the movement of said support. 5

5. In a machine tool having a movable work support and a rotatable tool support, the combination of transmission trains respectively for different of said supports and each including an element shiftable for altering the effect of the train with which it is associated, fluid operable shifting devices respectively for different of said elements, a fluid source, and control means operable to simultaneously connect said source with each of said devices, including a dog on 15 said work support and determinative of the time of operation of said control means.

6. In a milling machine, the combination of a movable work table, a rotatable tool spindle, a spindle train, a transmission for movement of 20 said table including a plurality of members each shiftable to alter the effect of said transmission, and shifting means for said members including a plurality of fluid operable devices respectively for the different of said members, a 25 fluid supply pump driven from said source, a plurality of channels respectively for connecting different of said devices, to be actuated by fluid from said pump, valve means associated with said channels for controlling fluid delivery 30 selectively to the one or the other of said devices, trip means for operation of said valve means, and a plurality of relatively adjustable dogs each supported from said table and respectively adapted to operate said valve means through said trip 35 means to connect said pump with different of said devices.

7. In a milling machine, the combination of a movable work table, a rotatable tool spindle, a spindle train including a power source, a transmission driven from said train for movement of 40 said table and including a plurality of members each shiftable to alter the effect of said transmission, a plurality of fluid operable shifting devices respectively for different of said members, a chamber containing fluid under substantial 45 pressure, a plurality of channels respectively for connecting said chamber with different of said devices, valve means associated with said channels for controlling fluid delivery from said 50 chamber selectively to the one or the other of said devices, a reservoir of fluid, and a pump adapted to supply fluid from said reservoir to said chamber and connected to be operated from said 55 source.

8. In a machine tool the combination of a movable member, a source of power, a train connectible from said source to said member and including an element shiftable for altering the effect of said train, a fluid operable device for 60 shifting said element, an accumulator providing a volume of fluid under substantial pressure and connectible for operation of said device, a reservoir, a pump connected to be driven from said power source and connected to deliver fluid to said accumulator, an inlet channel from said reservoir to said pump, a throttle adapted to restrict said inlet channel, and means controlling said throttle in accordance with the volume of fluid in said accumulator. 70

9. In a machine tool the combination of a rotatable tool spindle, a spindle support, a work support, a transmission including a power source, a motion interrupting clutch, and said spindle in the order recited, and mechanism for relative 75

- bodily movement of said supports including a fluid operable motor connected with one of said supports, a pump for the actuation of said motor, a plurality of trains respectively connected with 5 said transmission on opposite sides of said clutch, and means for alternatively connecting the one or the other of said trains to drive said pump.
10. In a machine tool the combination of a plurality of supports and mechanism for relative movement therebetween including a fluid operable motor connected with one of said supports, a pump for the actuation of said motor, power connections for said pump including means adjustable for a plurality of pump speeds respectively productive of different delivery volumes therefrom, other means adjustable for varying the volume delivered from said pump, and control mechanism for simultaneously adjusting each of said means.
15. In a machine tool the combination of a plurality of supports, and means for relative movement therebetween including a fluid operable motor connected with one of said supports, a power driven pump connected to drive said 20 motor, means adjustable for altering the delivery volume of said pump, a plurality of fluid operable devices for movement of said means in directions to increase and decrease the pump delivery volume respectively, a fluid source, and 25 control mechanism for selective connection of said source with the one or the other of said devices.
20. In a machine tool the combination of a plurality of supports and means for relative movement therebetween including a fluid operable motor connected with one of said supports, a power driven pump connected to drive said motor, means adjustable for altering the delivery volume of said pump, a plurality of fluid operable devices for movement of said means in 30 directions to increase and decrease the pump delivery volume respectively, a fluid source, and control mechanism for selective connection of said source with the one or the other of said devices.
25. In a machine tool the combination of a plurality of supports and means for relative movement therebetween including a fluid operable motor connected with one of said supports, a power driven pump connected to drive said motor, means adjustable for altering the delivery volume of said pump, a plurality of fluid operable devices for movement of said means in 35 directions to increase and decrease the pump delivery volume respectively, a fluid source, and control mechanism for selective connection of said source with the one or the other of said devices, and power operated 40 means for movement of said control mechanism at a predetermined point in the relative movement of said supports.
30. In a machine tool the combination of a movable support and transmission and control mechanism therefor, including a fluid operable motor connected therewith, a pump connected with said motor, a plurality of power connections respectively for fast and slow speed of said pump, whereby to vary the delivery volume thereof, other means adjustable for varying the volume of said pump, a first fluid operable device for 45 simultaneously effecting said slow speed connection and adjusting said means to reduce the volume of said pump, a second fluid operable device for simultaneously effecting said fast power connection and adjusting said means to increase the volume of said pump, a fluid source, and control mechanism for selective connection of said source to operate the one or the other of said devices.
35. In a machine tool the combination of a plurality of supports and transmission mechanism for relative movement therebetween including a fluid operable motor connected with one of said supports, a pump connected for actuation of said motor, a power transmission for driving said pump including means shiftable for a plurality of pump speeds whereby to vary the delivery 50 volume of said pump, and other means simultaneously available to vary the volume of pump delivery.
40. In a machine tool the combination of a work support and a tool support, transmission mechanism connectible for relative movement therebetween including a reverser and a rate changer, fluid operable shifting devices respectively for said reverser and rate changer, a constantly available source of fluid under pressure, a first valve device for connecting said source 55 with the shifter of said reverser, and a second valve device for connecting said source with the shifter of said rate changer, each of said devices being independently operable.
45. In a machine tool the combination of a power source, transmission mechanism connectible therewith including a clutch for interrupting said transmission and including elements shiftable for altering the effect of said transmission, fluid operable shifters for movement of said 60 elements, a fluid pump arranged to be driven from said main power source at a point unaffected by said clutch, an accumulator adapted to receive fluid from said pump, channels for selectively connecting said shifters with said accumulator, and mechanism to control the fluid delivery from said pump in accordance with the volume of fluid in said accumulator.
50. In a machine tool having a tool support and a work support, the combination of transmission and control mechanism for actuating one of said supports including a reverser shiftable to two positions respectively productive of support movement in different directions and to an intermediate position to stop support movement, first and second elements respectively operable to move said reverser to different of said two positions, a third element operable to move said reverser from either other position to said intermediate position, alternative power connections 65 for said elements, a dog operated trip normally adapted during movement of said support to effect the power connection of said third element whereby to stop said support, and means associated with said trip and adjustable to cause said trip to effect a power connection with one of said first or second shifters, whereby to change the direction of movement of said support.
55. In a milling machine having a rotatable spindle, a spindle support and a work support, the combination of a spindle train including a power source, a motion interrupting clutch and said spindle in the order recited, a transmission for relative movement of said supports and driven from said spindle train, said transmission including a reverser shiftable to different positions respectively productive of different directions of movement and to an intermediate stop position, three fluid operable elements respectively operable to move said reverser to different 70 of said positions, means for maintaining a continuously available supply of fluid for operating said elements including a pump and a driving train for said pump and connected with said spindle train at a point between said power source and clutch, valve means selectively adjustable to connect said fluid supply with said elements one at a time and, a dog operated trip for adjustment of said valve means and adapted during relative support movement to effect the fluid supply connection with the element for said stop position of the reverser.
60. In a machine tool having a rotatable spindle, a spindle support and a work support, the combination of a spindle train including a power 75

source, a motion interrupting clutch and said spindle in the order recited, a transmission for relative movement of said supports and connected to be driven from said spindle train at a point between said clutch and spindle, said transmission including an element shiftable to different positions whereby to alter the effect of said transmission, fluid operable shifting means for said element, means for continuously maintaining a supply of fluid available for operating said shifting means including a pump and a driving train for said pump and connected with said spindle train at a point between said power source and clutch and valve means selectively operable for connecting said fluid supply with said shifting means to shift said element to the one or the other of said different positions.

20. In a machine tool having a rotatable spindle, a spindle support and a work support, the combination of a spindle train including a power source, a motion interrupting clutch and said spindle in the order recited, a power train including a fluid operable motor connected with one of said supports and a pump for the actuation of said motor, a relatively slow feed train driven from said spindle train at a point between said clutch and spindle, a relatively fast quick traverse train driven from said spindle train at a point between said clutch and power source, and means for alternative connection of said fast or slow trains to actuate said pump.

21. In a milling machine the combination of a rotatable tool spindle, a work support movable in either direction in a path transverse to the axis of said spindle, a transmission for movement of said support including a reversibly fluid operable motor, a power driven pump selectively operable for any of a variety of relatively low feed rates and for a relatively high quick traverse rate of fluid delivery to said motor; and control means for said transmission including a dog operable mechanism for alternatively determining said fluid delivery at one of said variety of feed rates or at said quick traverse rate, a manually operable device adjustable independently of said mechanism for selectively predetermining said one of said variety of feed rates and a plurality of dogs respectively effective to operate said mechanism at intermediate points in different directions of support movement for operation of said mechanism.

22. In a milling machine the combination of a rotatable tool spindle, a work support movable in either direction in a path transverse to the axis of said spindle, a transmission for movement of said support including a reversibly fluid operable motor, a power driven pump selectively operable for any of a variety of relatively low feed rates and for a relatively high quick traverse rate of fluid delivery to said motor; and control means for said transmission including selectively dog operable mechanism for changing the direction or rate of said fluid delivery or for interrupting said fluid delivery, a manually operable device adjustable independently of said mechanism for selectively predetermining one of said variety of feed rates to be effective after subsequent operation of said mechanism to effect a feed rate of fluid delivery, a dog operable on said mechanism for effecting said change of direction of fluid delivery after said support has been moved in a forward direction, a dog operable on said mechanism for changing the rate of said fluid delivery at an intermediate point in the movement of said sup-

port in said forward direction whereby to effect said one of said variety of feed rates, and a dog operable on said mechanism for interrupting said fluid delivery after movement of said support in the other direction.

23. In a milling machine, the combination of a rotatable tool spindle, a work table movable in a path transverse to the axis of said spindle, a transmission for movement of said table including a fluid operable motor having a plurality of ports, a unidirectional output pump selectively operable for any of a variety of relatively low feed rates and for a relatively high quick transverse rate of fluid delivery, said pump having an inlet and an outlet port, and channels connectible for said outlet port of said pump to deliver fluid to one of said motor ports and simultaneously connectible to effect a substantially closed passageway from the other of said motor ports to said pump inlet port, said channels also having another connection; and control means for said transmission including valve means alternatively operable for effecting said simultaneous connections of said channels or to effect said other channel connection.

24. In a machine tool, the combination of a work support and a tool support, a transmission for actuation of one of said supports including a power source associated with said machine tool and adapted to be actuated at a substantially constant known number of revolutions per minute, a driven member and a rate changer connected to be driven from said source and connected to drive said member, said rate changer having portions adjustable to a variety of positions productive of corresponding rates of said member, means for adjusting said rate changer portions including a power train driven from said source to exclude said rate changer and connectible with said portions, control means for the connection of said power train with said rate changer portions including a manually operable lever, and means visibly indicating the result of the operation of said manually operable lever.

25. In a machine tool, the combination of a work support and a tool support, a transmission for actuation of one of said supports including a power source associated with said machine tool and adapted to be actuated at a substantially constant known number of revolutions per minute, a driven member and a rate changer connected to be driven from said source and connected to drive said member, said rate changer having portions adjustable to a variety of positions productive of corresponding rates of said member, means for adjusting said rate changer portions comprising a power train connectible with said rate changer portions including a fluid pump driven from said source to exclude said rate changer, a fluid channel connected with said pump, a member connected to operate said portions and to be fluid operated from said channel, valve means shiftable for controlling the passage of fluid through said channel, control means for the connection of said power train with said rate changer portions including a hand operable lever operable for shifting said valve means, and means visibly indicating the result of the operation of said hand lever.

26. In a milling machine, the combination of a hollow supporting structure, a tool spindle rotatably supported from said structure, a work table movably supported from said structure, a

- spindle transmission including a power source adapted to be actuated at constant speed and supported from said structure, a spindle rate changer and said spindle in the order recited, a 5 table transmission including a rate changer driven from said spindle transmission to exclude said spindle rate changer, one of said rate changers being housed within said hollow structure and comprising portions adjustable to a variety of 10 positions productive of corresponding rates, means for adjusting said rate changer portions including a power train driven from said source to exclude both said rate changers and connectible with said portions, control means for the 15 connection of said power train with said rate changer portions including a manually operable lever, and means exterior to said hollow structure and visibly indicating the result of the operation of said manually operable lever.
- 20 27. In a milling machine, the combination of a hollow supporting structure, a tool spindle rotatably supported from said structure, a work table movably supported from said structure, a spindle transmission including a power source 25 adapted to be actuated at constant speed and supported from said structure, a spindle rate changer and said spindle in the order recited, a table transmission including a rate changer driven from said spindle transmission to exclude said 30 spindle rate changer, one of said rate changers being housed within said hollow structure and comprising portions adjustable to a variety of positions productive of corresponding rates, means for adjusting said rate changer portions comprising a power train connectible with said rate 35 changer portions including a fluid pump driven from said source to exclude both said rate changers, a fluid channel and valve means shiftable for controlling the passage of fluid through said channel, control means for the connection of said power train with said rate changer portions including a hand operable lever connected with said valve means, and means exterior to said 40 hollow structure and visibly indicating the result of the operation of said hand operable lever.
- 45 28. In a machine tool, the combination of a work support and a tool support, a transmission for actuation of one of said supports including a power source associated with said machine tool and adapted to be actuated at a substantially 50 constant known number of revolutions per minute, a driven member and a rate changer connected to be driven from said source and connected to drive said member, said rate changer 55 having portions adjustable to a variety of positions productive of corresponding rates of said member, means for adjusting said rate changer portions comprising a rate selector adjustable to a variety of positions independently of the position of said rate changer portions, a power train, motion transmitting connections connected with said portions and connectible with said power train and operable to adjust said portions in accordance with the adjustment of said rate selector, a hand operated element controlling the 60 connection of said power train with said motion transmitting connections, and means visibly indicating the result of the operation of said hand operated element.
- 65 29. In a machine tool, the combination of a work support and a tool support, a transmission for actuation of one of said supports including a power source associated with said machine tool and adapted to be actuated at a substantially 70 constant known number of revolutions per min-
- ute, a driven member and a rate changer connected to be driven from said source and connected to drive said member, said rate changer having portions adjustable to a variety of positions productive of corresponding rates of said member, means for adjusting said rate changer portions comprising a rate selector adjustable to a variety of positions independently of the position of said rate changer portions, a power train including a fluid pump driven to exclude said 10 rate changer, a fluid operable device operable for movement of said rate changer portions in accordance with the adjustment of said rate selector, a fluid channel connectible between said pump and device, valve means shiftable for 15 controlling the passage of fluid through said channel, control means including a hand operable lever for shifting said valve means, and means visibly indicating the result of the operation of said hand lever.
- 20 30. In a milling machine, the combination of a hollow supporting structure, a tool spindle rotatably supported from said structure, a work table movably supported from said structure, a spindle transmission including a power source adapted to be actuated at constant speed and supported from said structure, a spindle rate changer and said spindle in the order recited, a table transmission including a rate changer driven from said spindle transmission to exclude said spindle rate 30 changer, one of said rate changers being housed within said hollow structure and comprising portions adjustable to a variety of positions productive of corresponding rates, means for adjusting said rate changer portions comprising a rate selector adjustable to a variety of positions independently of the position of said rate changer portions, a power train driven from said source to exclude both said rate changers, motion transmitting connections connected with said portions 40 and connectible with said power train, said motion transmitting connections being operable in accordance with the adjustment of said rate selector, a hand lever operable for controlling the connection of said power train with said motion transmitting connections, and means exterior to said hollow structure and visibly indicating the 45 result of the operation of said hand lever.
- 35 31. In a milling machine, the combination of a hollow supporting structure, a tool spindle rotatably supported from said structure, a work table movably supported from said structure, a spindle transmission including a power source adapted to be actuated at constant speed and supported from said structure, a spindle rate changer and said spindle in the order recited, a table transmission including a rate changer driven from said spindle transmission to exclude said spindle rate changer, one of said rate changers being housed within said hollow structure and comprising portions adjustable to a variety of positions productive of corresponding rates, means for adjusting said rate changer portions comprising a rate selector adjustable to a variety of positions independently of the position of said rate changer portions, a power train including a fluid pump driven from said source to exclude both said rate changers, a fluid operable device operable for movement of said rate changer portions in accordance with the adjustment of said rate selector, a fluid channel connectible between said pump and device, valve means shiftable for 50 controlling the passage of fluid through said channel, control means for shifting said valve means including a hand operable lever, and means 55
- 60
- 65
- 70
- 75

visibly indicating the result of the operation of said hand lever.

32. In a milling machine, the combination of a rotatable spindle, a work table movable relative to said spindle for work movement in a path transverse to the spindle axis, a power train for rotation of said spindle including a power source, a transmission element shiftable into a plurality of positions, and said spindle in the order recited, a table drive mechanism including feed and quick traverse mechanism driven from said source, and control mechanism including a device selectively fluid operable for shifting said transmission element to the one or the other of said positions, a pump driven from said source to exclude said transmission element, fluid channels connectible between said pump and said device, and valve means associated with said channels and controlling said selective operation of said device.

33. In a machine tool the combination of a base, a work table supported from said base for horizontal reciprocation, a spindle support supported from said base and uprising at the one side of a vertical plane passing through a longitudinal edge of said table, a tool spindle rotatably supported from said support and axially transverse to the direction of table movement, a spindle transmission including a power source, a transmission member shiftable for altering the spindle rotation, and said spindle in the order recited, alternatively operable feed and rapid traverse trains for movement of said work table, and control means for said spindle transmission comprising a fluid pump supported from said base, and a power train connecting said pump to be actuated from said spindle transmission at a point between said power source and transmission member, a fluid operable shifter for said member, a channel connectible from said pump to said fluid operable shifter, adjustable valve means associated with said channel, and a lever manually operable for effecting adjustment of said valve means and supported from said base at the other side of said vertical plane.

45. 34. In a milling machine, the combination of a transmission including a power source and a member to be actuated thereby, said transmission including means adjustable for determining various rates of actuation of said member relative to said power source, a device adjustable for pre-selecting a predetermined value of said relative rates which will be effected upon the subsequent adjustment of said adjustable means, and a secondary power transmission connectible for adjustment of said adjustable means including fluid shiftable piston devices and valve means operable to determine when said piston devices shall be shifted.

35. In a milling machine, the combination of a base, a work support supported from said base for horizontal reciprocation, a rotatable tool support, a structure carrying said tool support and uprising adjacent a longitudinal edge of said work support and at the one side of the vertical plane co-incident with said edge, a transmission connectible for actuation of one of said supports including a power source and means adjustable for determining various rates of actuation of the support relative to the rate of said source, a device adjustable for selectively determining one of said various rates, a secondary transmission connectible for adjustment of said adjustable means, and control means for said device including a manually operable portion supported from said base

at the other side of said vertical plane and adjacent the other edge of said work support.

36. In a milling machine, the combination of a rotatable tool support, a reciprocable work support, a transmission for actuation of one of said supports including a power source and means adjustable for establishing a plurality of rates of the actuated support relative to said source, a source of fluid under pressure, adjusting means for said adjustable means and operable from said fluid pressure source, manually operable valve means controlling the supply of fluid from said fluid source for selectively timing the effect thereof on said adjusting means, and a rate indicating device associated with said adjusting means and adjustable means to indicate the rate effected upon operation thereof.

37. In a milling machine, the combination of a rotatably movable tool support, a support bodily movable adjacent said tool support in a direction transverse to the axis thereof, a transmission for one of said movements driven at a substantially constant rate and operable for a variety of rates including a fast rate, a relatively slow rate and a plurality of intermediate rates, said transmission including a rate changer adjustable into a variety of different positions collectively productive of all of said rates and respectively determinative of different of said rates; and control mechanism for said transmission including a shifter operable to adjust said rate changer out of any of said positions of rate changer adjustment into any other thereof, said shifter providing a plurality of oppositely fluid operative pistons each connected for adjustment of said rate changer, a preselective device having various positions respectively determinative upon operation of said shifter of different of said positions of rate changer adjustment and movable independently of the position of adjustment of said rate changer and in advance of said operation of said shifter, a source of fluid under pressure, and manually operable means for the selective connection of said fluid source independently of the position of said preselective device and alternatively to actuate the one or the other of said pistons, said preselective device including a chart having markings respectively representing different of said rates, and means visibly indicating on said chart the effect of the operation of said control mechanism.

38. In a milling machine, the combination of a rotatably movable tool support, a support bodily movable adjacent said tool support in a direction transverse to the axis thereof, transmission mechanism for movement of said supports including a motion interrupting clutch for said tool support and a rate changer for one of said movements and adjustable into a variety of positions collectively productive of a fast rate, a relatively slow rate and a plurality of intermediate rates; and control mechanism for said transmission including a shifter operable to adjust said rate changer out of any of said positions and into any other thereof, said shifter providing a plurality of oppositely fluid operative pistons each connected for adjustment of said rate changer, a preselective device having various positions respectively determinative upon operation of said shifter of different of said positions of rate changer adjustment and movable independently of the position of adjustment of said rate changer in advance of operation of said shifter, a source of fluid under pressure, manually operable means controlling said clutch, and fluid con-

- nections controlled from said manually operable means for connecting said fluid source to actuate said pistons, said preselective device including a chart having markings respectively representing different of said rates, and means visibly indicating on said chart the effect of the operation of said control mechanism.
39. In a milling machine, the combination of a horizontally movable work table, a supporting structure therefor, a rotatably movable tool spindle at a level above said table and axially transverse to the path of table movement, said structure providing a spindle supporting portion uprising adjacent a longitudinal edge of said table at one side of a vertical plane passing through said edge, a transmission for one of said movements including a rate changer adjustable into a variety of positions collectively productive of a fast rate, a relatively slow rate and a plurality of intermediate rates; and control mechanism for said transmission including a shifter operable to adjust said rate changer out of any of said positions of rate changer adjustment into any other thereof, said shifter providing a plurality of oppositely fluid operable pistons each connected for adjustment of said rate changer, a preselective device having various positions respectively determinative upon operation of said shifter of different of said positions of rate changer adjustment and operable independently of the position of adjustment of said rate changer in advance of said operation of said shifter, said device including a portion exposed for manual operation at the other side of said vertical plane, a source of fluid under pressure and manually operable means for the selective connection of said fluid source independently of the position of said preselective device and alternatively to actuate the one or the other of said pistons, said preselective device including a chart having markings respectively representing different of said rates, and means visibly indicating on said chart the effect of the operation of said control mechanism.
40. A milling machine including a bed, a tool spindle support carried by the bed having a spindle journaled therein, a work support carried by the bed, and shiftable relative to the spindle, a prime mover, a power transmission including variable speed gearing operatively connecting the prime mover and spindle, means for effecting power movement of the work support including a second variable speed transmission, power means for varying the rate transmitted by one of said variable speed transmissions, and a control device on the shiftable member and coupled with said power means for controlling the operation thereof.
41. A milling machine including a column, a cutter spindle and a work support mounted on the column, a prime mover carried thereby, variable speed connections between the prime mover and the spindle for rotation of the spindle, additional variable speed connections from the prime mover for effecting a relative shifting of the spindle and work support one with respect to the other, clutch means for determining the operative connection of the feed mechanism and the spindle rotating mechanism, a single control for jointly determining the operative effect of the clutch mechanism, an independent quick traverse drive transmission in constant operative connection with the prime mover and means for coupling the quick traverse with the shiftable member when the control member has rendered the other drive connections ineffective.
42. A milling machine including a column, a cutter spindle rotatably supported thereby, a work support supported by the column, feeding means for imparting relative movement to the work support with respect to the spindle, a prime mover, a transmission from the prime mover to the spindle including a clutch and an organized speed variator disposed in serial relation in the transmission, a second transmission deriving power from the first transmission line at a point intermediate the prime mover and clutch whereby said second transmission is unaffected by the clutch, a first branch transmission extending from the second transmission to the feeding means, a second branch transmission extending to the feeding means and including an organized variable speed unit, clutch means alternatively available to couple the first or second branch transmission to the feeding means, a single actuator for simultaneously shifting the spindle drive clutch and second branch transmission clutch in the inoperative position and additional means for shifting the first branch transmission clutch for operative coupling of the first branch transmission and feeding means when the second branch transmission is disconnected therefrom.
43. In a milling machine, the combination of a bodily movable work support, a rotatably movable tool support, a transmission for one of said movements including a motion interrupter and a plurality of members each shiftable to alter the effect of said transmission, a plurality of fluid operable shifting devices respectively for different of said members, a chamber containing fluid under substantial pressure, a plurality of channels respectively for connecting said chamber with different of said devices, valve means associated with said channels for controlling fluid delivery from said chamber selectively to the one or the other of said devices, a reservoir of fluid, and a pump driven from said transmission to exclude said motion interrupter and adapted to supply fluid from said reservoir to said chamber.
44. In a machine tool the combination of a power source, transmission mechanism connectible therewith including a clutch for interrupting said transmission and including elements shiftable for altering the effect of said transmission, fluid operable shifters for movement of said elements, a fluid pump arranged to be driven unaffected by said clutch, an accumulator adapted to receive fluid from said pump, channels for selectively connecting said shifters with said accumulator, and mechanism to control the fluid delivery to said accumulator to maintain a predetermined pressure therein.
45. In a machine tool having a rotatable spindle, a spindle support and a work support, the combination of a spindle train including a power source, a motion interrupting clutch and said spindle in the order recited, a transmission for relative movement of said supports, said transmission including an element shiftable to different positions whereby to alter the effect of said transmission, fluid operable shifting means for said element, means for continuously maintaining a supply of fluid available for operating said shifting means including a pump and a driving train for said pump connected with said spindle train at a point between said power source and clutch and valve means selectively operable for connecting said fluid supply with said shifting means to shift said element to the one or the other of said different positions.
46. A milling machine having a work table, a

frame member supporting the work table for movement, a prime mover mounted on said frame member, means for coupling the prime mover to the table for actuation at variable feed and rapid traverse rates, a feed-rapid traverse device selectively shiftable to connect the table for the one or the other rate, fluid operable means for shifting said device, a table reverser device, fluid operable means for shifting said reverser device, means actuated by said prime mover for supplying pressure to the device shifting means, control valves for the different device shifting means, and trip mechanism in operative relation to the table for automatically positioning both of said control valves.

47. In a milling machine the combination with a movable support of power actuated transmission means for moving said support including a fluid actuated rate determining device and a fluid actuated direction determining device, fluid pressure means for said devices, an independently operable control valve for each device, and a common control member for both valves.

48. A milling machine having a rotatable cutter spindle and a reciprocable work table, power actuated means including a motion interrupting clutch for rotating the spindle, power actuated means including a trip plunger for reciprocating the table transversely of the spindle, a common prime mover for said power actuated means, power operated means including a control member for shifting said clutch, means operatively connecting the control member to the trip plunger, and means carried by the table for shifting said plunger to determine simultaneously the rate of movement of the table and rotation of said spindle in accordance with said rate.

49. A milling machine having a rotatable cutter spindle and a reciprocable work table, a spindle transmission including a motion interrupting clutch, a table transmission for effecting movement of the table transversely of the spindle, a common prime mover for the table and spindle transmissions, a fluid operable device for shifting said clutch, a source of pressure, a valve for determining the flow of pressure to said device, trip controlled mechanism effective upon the transmission for determining movement of the table in one direction at two different rates, and means operatively coupling the valve to said mechanism whereby the cutter will be stopped during movement at one of said rates.

50. In a machine tool, the combination with a work support and a tool support mounted for

relative movement, of a transmission mechanism arranged to effect relative movement of said supports, said transmission mechanism including a rate changer adjustable to effect said relative movement at any one of a plurality of rates of speed, means disposed to adjust said rate changer to thereby effect any one of said rates of speed, said means including a rate selector adjustable independently of said rate changer and disposed to predetermine a subsequent adjustment of said rate changer and power driven means operable to adjust said rate changer in accordance with the preselected adjustment of said rate selector, and control means disposed to control the operation of said power driven adjusting means in manner to selectively effect adjustment of said rate changer to cause said relative movement to occur at the preselected one of said rates.

51. A machine tool including a frame, a tool spindle rotatably supported by said frame, a work support carried by said frame in manner to be movable relative to said tool spindle, a source of power associated with said machine tool, a power transmission mechanism operatively connecting said source of power to said tool spindle in manner to rotate said spindle, means for effecting power movement of said work support including a variable speed transmission mechanism, power operated means arranged to adjust said variable speed transmission mechanism to vary the rate of movement effected thereby, and a control device carried by said movable work support and operatively connected to control the operation of said power operated rate varying means.

52. In a machine tool having a bed, a tool spindle rotatably supported by said bed, and a work support carried by said bed and shiftable relative to said tool spindle in cooperative relationship therewith, the combination with a source of power and a power transmission mechanism operatively connecting said source of power to said tool spindle to rotate it, of means for effecting power shifting of said work support including a variable speed power transmission mechanism operatively connecting said source of power to said work support, power means operatively connected in manner to adjust said variable speed transmission mechanism to vary the rate of shifting of said work support, and a control device disposed to be operated by movement of said shiftable work support and operatively associated with said rate adjusting power means in manner to control the operation thereof.

FRED A. PARSONS.

CERTIFICATE OF CORRECTION.

Patent No. 2,052,647.

September 1, 1936.

FRED A. PARSONS.

It is hereby certified that error appears in the printed specification of the above numbered patent requiring correction as follows: Page 6, first column, line 68, claim 3, for the word "devices" read elements; and that the said Letters Patent should be read with this correction therein that the same may conform to the record of the case in the Patent Office.

Signed and sealed this 3rd day of November, A. D. 1936.

Henry Van Arsdale

Acting Commissioner of Patents.

frame member supporting the work table for movement, a prime mover mounted on said frame member, means for coupling the prime mover to the table for actuation at variable feed and rapid traverse rates, a feed-rapid traverse device selectively shiftable to connect the table for the one or the other rate, fluid operable means for shifting said device, a table reverser device, fluid operable means for shifting said reverser device, means actuated by said prime mover for supplying pressure to the device shifting means, control valves for the different device shifting means, and trip mechanism in operative relation to the table for automatically positioning both of said control valves.

47. In a milling machine the combination with a movable support of power actuated transmission means for moving said support including a fluid actuated rate determining device and a fluid actuated direction determining device, fluid pressure means for said devices, an independently operable control valve for each device, and a common control member for both valves.

48. A milling machine having a rotatable cutter spindle and a reciprocable work table, power actuated means including a motion interrupting clutch for rotating the spindle, power actuated means including a trip plunger for reciprocating the table transversely of the spindle, a common prime mover for said power actuated means, power operated means including a control member for shifting said clutch, means operatively connecting the control member to the trip plunger, and means carried by the table for shifting said plunger to determine simultaneously the rate of movement of the table and rotation of said spindle in accordance with said rate.

49. A milling machine having a rotatable cutter spindle and a reciprocable work table, a spindle transmission including a motion interrupting clutch, a table transmission for effecting movement of the table transversely of the spindle, a common prime mover for the table and spindle transmissions, a fluid operable device for shifting said clutch, a source of pressure, a valve for determining the flow of pressure to said device, trip controlled mechanism effective upon the transmission for determining movement of the table in one direction at two different rates, and means operatively coupling the valve to said mechanism whereby the cutter will be stopped during movement at one of said rates.

50. In a machine tool, the combination with a work support and a tool support mounted for

relative movement, of a transmission mechanism arranged to effect relative movement of said supports, said transmission mechanism including a rate changer adjustable to effect said relative movement at any one of a plurality of rates of speed, means disposed to adjust said rate changer to thereby effect any one of said rates of speed, said means including a rate selector adjustable independently of said rate changer and disposed to predetermine a subsequent adjustment of said rate changer and power driven means operable to adjust said rate changer in accordance with the preselected adjustment of said rate selector, and control means disposed to control the operation of said power driven adjusting means in manner to selectively effect adjustment of said rate changer to cause said relative movement to occur at the preselected one of said rates.

51. A machine tool including a frame, a tool spindle rotatably supported by said frame, a work support carried by said frame in manner to be movable relative to said tool spindle, a source of power associated with said machine tool, a power transmission mechanism operatively connecting said source of power to said tool spindle in manner to rotate said spindle, means for effecting power movement of said work support including a variable speed transmission mechanism, power operated means arranged to adjust said variable speed transmission mechanism to vary the rate of movement effected thereby, and a control device carried by said movable work support and operatively connected to control the operation of said power operated rate varying means.

52. In a machine tool having a bed, a tool spindle rotatably supported by said bed, and a work support carried by said bed and shiftable relative to said tool spindle in cooperative relationship therewith, the combination with a source of power and a power transmission mechanism operatively connecting said source of power to said tool spindle to rotate it, of means for effecting power shifting of said work support including a variable speed power transmission mechanism operatively connecting said source of power to said work support, power means operatively connected in manner to adjust said variable speed transmission mechanism to vary the rate of shifting of said work support, and a control device disposed to be operated by movement of said shiftable work support and operatively associated with said rate adjusting power means in manner to control the operation thereof.
